UNITED STATES PATENT OFFICE.

JAMES PAULL, OF WELLSBURG, WEST VIRGINIA.

DESIGN FOR A GLASS JAR.

No. 37,525.

Specification for Design.

Patented Sept. 5, 1905.

Application filed May 18, 1905. Serial No. 261,079. Term of patent 14 years.

To all whom it may concern:

Be it known that I, JAMES PAULL, of Wellsburg, in the county of Brooke and State of West Virginia, have invented a new, original, and ornamental Design for a Glass Jar, reference being had to the accompanying drawings, forming part of this specification, in which—

Figure 1 is a top plan view of the glass jar, and Fig. 2 is a side view of the same.

I claim—

The ornamental design for a glass jar, as shown.

JAMES PAULL.
